US0D1106442S

(12) **United States Design Patent** (10) **Patent No.:** **US D1,106,442 S**
(45) **Date of Patent:** **** Dec. 16, 2025**

(54) **ORAL IRRIGATOR**

(71) Applicant: **Aimi Health Technology (Guangdong) Co., Ltd**, Dongguan (CN)

(72) Inventor: **Yingjia Liu**, Dongguan (CN)

(73) Assignee: **Aimi Health Technology (Guangdong) Co., Ltd**, Dongguan (CN)

(**) Term: **15 Years**

(21) Appl. No.: **29/942,735**

(22) Filed: **May 16, 2024**

(30) **Foreign Application Priority Data**

Nov. 20, 2023 (CN) 202330756663.6

CLAIM

The ornamental design for an oral irrigator as shown and described.

DESCRIPTION

FIG. 1 is a front view of an oral irrigator, showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front top perspective view thereof;

FIG. 8 is a left top perspective view thereof; and,

FIG. 9 is a back bottom perspective view thereof.

The broken lines depict portions of the oral irrigator that form no part of the claimed design.

1 Claim, 9 Drawing Sheets
